(Cl. D61—1)

To all whom it may concern:

Be it known that I, Lysle G. Tatro, a citizen of the United States, residing at Los Angeles, in the county of Los Angeles and State of California, have invented a new, original, and ornamental Design for a Combined Flash Lamp Igniter and Camera Shutter Synchronizer, of which the following is a specification, reference being had to the accompanying drawing, forming a part thereof.

Fig. 1 is a perspective view of the combined flash lamp igniter and camera shutter synchronizer, showing my new design;

Fig. 2 is a side elevational view of the same;
Fig. 3 is a top plan view of the same; and
Fig. 4 is a bottom plan view of the same.

The dominant feature of my design resides in the portion shown in full lines.

I claim:

The ornamental design for a combined flash lamp igniter and camera shutter synchronizer, as shown.

LYSLE G. TATRO.
